ROTARY BRUSH FOR SUCTION CLEANERS

William Douglas Sellers, Pasadena, Calif., assignor to The Hoover Company, North Canton, Ohio, a corporation of Ohio

Application December 9, 1947, Serial No. 790,544

6 Claims. (Cl. 15—183)

1

This invention relates to suction cleaners and more particularly to the manner of mounting a removable brush element on a rotatable brush or agitator body.

When rotatable brushes or agitators are mounted in the suction nozzle of a suction cleaner space is at a premium. The ideal situation is for the bristles of the brush or agitator to extend the full length of the nozzle. However, it is necessary to mount the brush or agitator for rotation and to provide means for rotatably driving it. Both of these factors have heretofore limited the extent of the bristles of the brush or agitator along the length of the nozzle.

It is an object of this invention to provide a removable brush element for a rotatable brush or agitator, adapted for placement in a suction cleaner nozzle, in which the bristles extend the greatest possible distance along the length of the nozzle.

In rotary brushes or agitators for use in the nozzle of a suction cleaner it is desirable that the bristles extend helically about the body of the brush or agitator roll. In the past this has been complicated because of the difficulty in spirally shaping the bristle holder and in forming a spiral seat for the brush element in the brush or agitator roll.

According to this invention it is unnecessary to helically form the bristle holder or to form a helical seat for the brush element in the body of the brush or agitator roll.

It is well known that the bristles of a rotary brush or agitator as used in a suction cleaner nozzle wear away with use. It is therefore necessary to provide some way for easily replacing the brush element as the bristles become worn.

Accordingly another object of this invention is to mount the brush element upon the agitator body that it can be easily removed and replaced when the bristles become worn.

Other objects and advantages of this invention will become apparent as the description proceeds and upon considering in connection therewith the accompanying drawing in which:

Figure 1 is a side elevation of a suction cleaner incorporating a rotatable brush or agitator in accordance with this invention with certain parts of the suction cleaner broken away;

Figure 2 is a perspective view of the rotary brush or agitator of this invention;

Figure 3 is a perspective view of the bristle-holding element of this invention; and

Figure 4 is a cross-sectional view through the

2

brush or agitator of this invention taken on line 4—4 of Fig. 2.

Referring to the drawing, a suction cleaner as illustrated comprises a nozzle 1 interiorly connected by an air passageway 2 to a fan chamber 3 which houses a suction-creating fan 4 carried by the lower end of a motor shaft 5, an unshown motor being positioned within a motor casing 6 immediately above the fan chamber. The nozzle 1 is formed with front and rear surface-contacting lips 7 and 8 between which the cleaning air enters to be drawn by the rotating fan through the air passageway 2 and discharged through an exhaust outlet 11 into a dust bag 9 removably connected to the outlet 11 by manually operable nuts 12. The machine is movably supported upon front wheels 13 and rear wheels 14 and is provided with a pivoted handle 15 by which it may be propelled over the floor or other surface being cleaned.

Within the nozzle 1 is a brush or agitator 16 rotatably mounted upon a shaft 17 and driven by a belt 18 from the motor shaft 5. As is usual the brush or agitator 16 is so mounted that the bristles will extend slightly beyond or below the plane of nozzle lips 7 and 8.

The brush or agitator 16 includes a metal shell 20 and a plurality of bristle-holding elements 21, a belt pulley 22 being formed in the shell 20 mid-way between its ends. The bristle-holding elements 21 may be of the same shape and size and of moldable material such as hard rubber, a phenolic condensation product or other suitable material; or they may be fabricated of metal.

The edge 23 of the elements 21 is straight while the edge 24 is of spiral formation. Adjacent the spiral edge 24 the bristle-holding elements 21 are provided with a row of bristle tuft-receiving openings 25 in which bristle tufts 26 are secured. A plurality of counter-sunk openings 27 are provided in the elements 21 to receive screws 28 for attaching the elements to the shell 20. It is to be noted that the screw-receiving openings 27 are all positioned to one side of the bristle tuft-receiving openings 25 so that the row of bristle tufts may be extended to the extreme end of the elements.

The metal of the shell 20 is depressed inwardly 50 upon opposite sides of pulley 22 to form recessed seats for the bristle-holding elements 21, each seat including a pair of ledges 30 and 31 and side walls 32 and 33. The ledge 31 is wider in each instance than the ledge 30 and has screw threaded holes therein to receive the screws 28.

The wall 32 of the depression is straight so as to conform to the straight side wall 23 of the bristle-holding elements 21 while the wall 33 extends spirally to enable it to abut the edge 24. In section the bristle-holding elements 21 conform to a segment of a circle and completely fill their seats in the shell 20, their outer surfaces forming smooth continuations of the latter.

It is to be noted that the depressions and also the bristle-holding elements 21 extend to positions closely adjacent the pulley 22 and to the agitator end pieces 34 carried on the shaft 17 so that the bristle rows extend a maximum distance in the direction of the length of the nozzle. This is made possible in part by the fact that the attaching screws 28 are positioned at the side of the row of bristle tufts 26 rather than at the ends thereof.

In order to remove the bristle-holding elements 21 when the bristles become worn it is only necessary to unscrew the screws 28, remove the old element, and replace it with a new one. The old elements may, if desired, be rebristled for reuse. It is also to be noted that the bristle-holding elements are interchangeable so that their replacement provides no special problem.

I have shown but a single embodiment of my invention which, it is to be understood, is to be taken as illustrative only and not in a limiting sense. I do not wish to be limited to the particular structure shown and described but to include all equivalent variations thereof except as limited by the scope of the claims.

I claim:

1. A brush roll comprising, a hollow elongated generally cylindrical shell having a depression within its length to form a belt pulley and a plurality of shallow depressed portions extending from said pulley to the ends of said shell for receiving bristle-holding elements, each of said depressed portions having a straight side wall and a wall spaced peripherally therefrom extending helically along said shell, the bottom wall of said depressed portions being transversely arched between said walls and concentric with the periphery of said shell and bristle-holding elements in said depressed portions of the same shape and size as said depressed portions.

2. A cylindrical brush adapted to be positioned in the nozzle of a suction cleaner comprising, a hollow generally cylindrical elongated shell having a central circumferential depression to form a belt pulley, a plurality of shallow depressed portions in said shell at the sides of said pulley extending from closely adjacent thereto to closely adjacent the ends of said shell, each of said depressed portions having a straight side wall and a side wall spaced peripherally therefrom and extending helically along the length of said shell, supporting ledges extending toward each other from the bottom of said walls, said ledges being transversely arcuate and concentric with the periphery of said shell, bristle-holding elements positioned in said depressed portions of the same shape and size as said depressed portions and resting on said ledges, and means for securing said bristle-holding elements to said ledges.

3. A cylindrical brush adapted to be positioned in the nozzle of a suction cleaner comprising, a hollow elongated generally cylindrical shell having a central depression forming a belt pulley, a plurality of shallow depressed portions in said shell at the sides of said pulley extending from

closely adjacent thereto to closely adjacent the ends of said shell, each of said depressed portions having peripherally spaced side walls extending longitudinally of said shell, ledges extending toward each other from the bottoms of said walls, said ledges being transversely arcuate and concentric with the periphery of said shell, elongated bristle-holding elements positioned in said depressed portions so as to lie against said walls and ledges, said elements being transversely arcuate and of a thickness the same as the depth of said depressed portions, a row of bristle tufts extending along one edge of said bristle-holding elements from end to end thereof, and means within the length of said row of bristles for securing said bristle-holding elements to said ledges.

4. A cylindrical brush adapted to be positioned in the nozzle of a suction cleaner comprising, a hollow elongated generally cylindrical shell having a central peripheral depression forming a belt pulley, a plurality of shallow depressed portions in said shell extending from closely adjacent said pulley to closely adjacent the ends of said shell, said depressed portions having one side wall extending in a straight line longitudinally of said shell and a second wall spaced peripherally of said one wall and extending helically along the length of said shell, the bottom wall of said depressed portions being transversely arched between said walls and concentric with the periphery of said shell, a bristle-holding element positioned in each of said depressed portions, said bristle-holding element having a straight edge and a helical edge to extend along the spaced walls of said depressed portions, said elements being transversely arcuate and of a thickness the same as the depth of said depressed portions, a row of bristle tufts positioned along the helical edge of said bristle-holding elements and extending from end to end thereof, and means for securing said bristle-holding elements to said shell.

5. A cylindrical brush adapted to be positioned in the nozzle of a suction cleaner comprising, a hollow elongated generally cylindrical shell having a central peripheral depression forming a belt pulley, a plurality of shallow depressed portions in said shell extending from closely adjacent said pulley to closely adjacent the ends of said shell, said depressed portions having one side wall extending in a straight line longitudinally of said shell and a second wall spaced circumferentially from said one wall and extending helically along the length of said shell, ledges extending toward each other from the bottoms of said walls, said ledges being transversely arcuate and concentric with the periphery of said shell, a brush-holding element positioned in each of said depressed portions abutting said ledges, said bristle-holding elements being transversely arcuate and of a thickness the same as the depth of said depressed portions and having a straight edge and a helical edge to extend along the peripherally spaced walls of said depressed portions, a row of bristle tufts positioned along the helical edge of said bristle-holding elements and extending from end to end thereof, and means for securing said bristle-holding elements to said ledges.

6. A bristle holding element adapted to form a portion of the periphery of a cylindrical brush comprising, a transversely arcuate elongated member forming a segment of an annulus, said member having a straight edge extending in a straight line from one of its ends to the other

and a helically formed edge also extending between said ends, a row of bristle tufts extending from end to end of said member along the helical edge thereof and fastener-receiving openings extending through said member along the straight edge thereof.
